WARREN L. MCLEAN, OF SAN FRANCISCO, CALIFORNIA, ASSIGNOR OF ONE-HALF TO
JOHN A. VAN BEAL, OF SAN FRANCISCO, CALIFORNIA.

COMBINED CONCENTRATING AND AMALGAMATING MACHINE.

1,169,083.

Specification of Letters Patent. Patented Jan. 18, 1916.

Application filed January 5, 1915. Serial No. 605.

To all whom it may concern:

Be it known that I, WARREN L. MCLEAN, a citizen of the United States, residing in the city and county of San Francisco and State of California, have invented new and useful Improvements in Combined Concentrating and Amalgamating Machines, of which the following is a specification.

This invention relates to a combined concentrating and amalgamating machine.

It is one of the objects of the present invention to produce a concentrator for handling gold-bearing sand, and particularly to separate the coarser gold by concentration and the fine or "flour" gold by amalgamation.

Another object is to produce an apparatus in the nature of a "knock-down" structure that may be readily taken apart for shipment and put together again by a person of ordinary ability; furthermore, to produce an apparatus that is simple in construction, efficient and durable in operation, and which is so arranged that the water may be reused, practically speaking, indefinitely.

The invention consists of the parts and the construction and combination of parts as hereinafter more fully described and claimed, having reference to the accompanying drawing, in which

Figure 1 is a central longitudinal section through the machine. Fig. 2 is a detail view of the baffle plate adjusting mechanism. Fig. 3 is an end view, partly in section.

Fig. 4 is a cross section on line 4—4, Fig. 1.

More particularly described, A indicates a suitable frame. Suitably supported by said frame upon spring arms 2 is a horizontally positioned frame 3, and mounted on said frame and angularly adjustable thereon by means of a screw 4 and pivot 5 is a concentrating table 6, the upper face of which is covered with burlap, canvas, or any other similar material 7, said covering 7 being secured thereon by a series of riffle strips 8 positioned crosswise of the table.

Vibrating or shaking movement is transmitted to the table laterally, with relation to the flow of the material treated, by any suitable means, or, as here shown, by an eccentric 8^a and a link 9 connected with frame 3, as at 10. Water is preferably delivered to the head end of the table by a centrifugal pump 11 through a stand pipe 12 and a hori-

zontally positioned, perforated launder 13. 55 The pump may be driven from any suitable source of power and eccentric 8^a may be driven by or mounted on the pump shaft, as shown.

Suitably secured in frame A, just below 60 the discharge end of the concentrating table, is a box-like frame 14 within which is mounted a plurality of superposed amalgamating plates 15. These plates are carried by brackets 16 and are set on a suitable incline, being adjustable with relation to each other in a longitudinal direction. The bottom of frame 14 is also provided with a series of amalgamating plates 17 offset with relation to each other, as indicated at 18, 70 and the frame is further provided with an amalgam trap 19 through which the discharge of all the plates passes before emptying into a trap or well 20 extending along one side of the main frame. The well is divided into two compartments 21 and 22 by a partition plate 23. The solid material, such as sand, settles in compartment 21 while the water overflows into the second compartment 22 where it is taken up by a pipe 80 24 connected with the suction side of the pump. The water may in this manner be returned to the head of the concentrating table and can, practically speaking, be reused indefinitely. 85

Mounted above frame 14 is a grizzly 25, and adjustably mounted within the frame, just in front of the discharge ends of plates 17, is a baffle plate 26, the function of which will later be described. 90

The machine constructed as here shown is particularly adapted to handle gold-bearing sands and gravels, and this material is delivered to the head end of the table when the machine is operating in any suitable manner by a feed launder 27. The sand and water mixing at the point will gradually work down over the riffles of the table and will finally discharge on the grizzly 25 where the coarser gravel and rocks will be caught and conveyed to the tailing heap, while the water and sand will pass through into frame 14 where it is caught by the several amalgamating plates 15 and 17. The material will here flow over the plates and will finally pass through the amalgam trap and discharge into the well, the sand settling in the first compartment while the water over-

flows into the second compartment to be again returned to the table, as described.

In actual practice it is found that the coarser gold settles on the concentrating table, while the finer or "flour" gold passes over with the sand and water. This gold is, however, caught by the amalgamating plates as a very large surface is presented to the material handled. The amalgam trap 10 is only provided for the purpose of catching any amalgam that may be scoured off or otherwise lost from the plates.

The baffle plate 26 may be adjusted to any suitable angle, with relation to the discharge 15 ends of plates 15, by means of the clamp screw 30. The baffle plate leads the discharging material and water from the upper plates back onto the lower plates 17, thereby giving any escaping gold a further 20 chance to be caught. The baffle plate also reduces the height or drop of material from the upper plates, thereby preventing too much agitation on the lower plates or in the amalgam trap.

25 The mounting of the upper superposed plates on brackets, as shown, permits these to be adjusted longitudinally with relation to each other. The plates may in this manner be adjusted to a position where each 30 plate will receive and handle an equal amount of material.

The machine as a whole is simple and substantial in construction and can easily be knocked down for shipment or assembled at 35 any place by a person of ordinary ability.

The materials and finish of the several parts of the machine are such as the experience and judgment of the manufacturer may dictate.

40 I wish it understood that various changes in form, proportions and minor details of construction may be resorted to within the scope of the appended claims and that I do not wish to limit myself to the specific design and construction here shown.

Having thus described my invention, what I claim and desire to secure by Letters Patent—

50 1. In a machine of the character described, a plurality of inclined superposed amalgamating plates, means for adjusting said plates longitudinally with relation to each other, a baffle plate adjacent the discharge ends of the plates swingable toward and 55 away from the latter, and means to hold the

baffle plate rigidly in any selected position thereof.

2. In a machine of the character described, a plurality of inclined superposed amalgamating plates, means for adjusting said plates longitudinally with relation to each other, and a baffle plate adjustably mounted with relation to the discharge ends of the amalgamating plates. 60

3. In a machine of the character described, a plurality of inclined superposed amalgamating plates, means for adjusting said plates longitudinally with relation to each other, a plurality of stationary amalgamating plates offset with relation to each other 70 mounted below the first named plates, and a baffle plate adjustably mounted with relation to the discharge ends of the amalgamating plates.

4. In combination with a plurality of inclined superimposed amalgamating plates, baffle means disposed adjacent the discharge ends of said plates and being common to all of the latter, and means to allow said baffle means to be set at varying angular positions with respect to said plates. 75

5. In a machine of the type set forth, a lower inclined amalgamating plate, a series of upper longitudinally adjustable superposed amalgamating plates arranged above 85 the lower plate and having their ends spaced from the respective ends of the lower plate, an inlet above the upper plates extending the length of the lower plate and baffle means arranged in front of the upper plates 90 and above the lower plate and disposed between the front ends of the upper plates and the front end of the lower plate.

6. In combination with a series of inclined superposed amalgamating plates, baffle 95 means adjacent the discharge ends of said plates, said baffle means being common to and extending across the discharge ends of all of the plates and in angular relation to the latter, and means whereby to enable the angular relation between the plates and baffle means to be varied. 100

In testimony whereof I have hereunto set my hand in the presence of two subscribing witnesses.

WARREN L. MCLEAN.
